(57) **CLAIM**

We claim the ornamental design for a stopper clip, as shown and described.

DESCRIPTION

This is related to U.S. patent application Ser. No. 29/376,049, entitled Stopper Clip filed on Sep. 30, 2010, and U.S. patent application Ser. No 29/376,050, entitled Bracelet Stopper Clip filed on Sep. 30, 2010, the disclosures of which are incorporated by reference.

FIG. 1 is a front, left side, top view of a stopper clip in a closed position showing our new design;

FIG. 2 is a left side, top, rear view thereof in open condition with functional elements shown in broken lines for environmental purposes only;

FIG. 3 is front, left side, top view thereof in open condition with functional elements shown in broken lines for environmental purposes only;

FIG. 4 is a left side, top, rear view thereof in open condition with functional elements shown in broken lines for environmental purposes only; and,

FIG. 5 is an environmental view illustrating the use of two of the stopper clips of FIG. 1 mounted to a bracelet and used to position charms along the bracelet.

The broken line showing of the bracelet is for the purpose of showing environment and forms no part of the claimed design.

The stopper clip is used to position charms along a bracelet as illustrated in FIG. 5.
